SAFETY RAZOR

Harry Beckham Randolph, London, England

Application February 11, 1932. Serial No. 592,245

2 Claims. (Cl. 30—12)

This invention comprises improvements in safety razors. It is an object of the invention to provide a safety razor of the self-stropping type with which stropping can be accomplished more effectively than in the usual type of such razors, and in which in particular the pressure of the blade upon the strop is both adequate and uniform, the possibility of the blade accidentally cutting the strop is reduced to a minimum, and it is possible effectively to strop razor blades of the solid hollow ground type as distinct from wafer blades in the razor frame without removal of the blade.

Further objects of the invention are to provide improved means for holding said hollow ground blades, improved means for adjusting the guard relatively to the blade, and a more rigid frame for the razor.

To this end the invention comprises various combinations of parts, specific forms of which are hereinafter described, and the essential features of which are pointed out in the appended claims.

The invention will now be described by way of example with reference to the accompanying drawing which illustrates one embodiment of the invention.

In the drawing:—

Figure 1 is an external side elevation of a razor, Figure 2 is a central vertical section through the same,

Figure 3 is an underside plan view with the handle removed, and

Figures 4 and 5 are details.

Referring to Figures 1 to 3, the razor comprises a strop-engaging carriage in the form of a rectangular base plate 11, having upstanding ribs 35, 36 along its front and rear edges, which carries at its ends upstanding lugs 12. The base plate 11 may conveniently be formed of extruded metal. The lugs 12 are separate from the base plate and carry horizontal extensions 13 (Figure 3) which underlie the base plate and are secured thereto by screws 14.

A blade 27 is held in a spring-clip holder 32 which is secured upon an operating pivot 33 which passes through the lugs 12. The lugs 12 are further stiffened by means of a cross-bar 34 which extends between them.

A roller-type guard 15 is mounted between lugs 16 on a sliding frame 17. The slide 17, as will be noted, is integral with the cross member 18 of the frame and the lugs 16. The external width of the slide 17 is such as to fit closely between the end faces of the horizontal extensions 13 of

the lugs 12 which are secured to the underside of the carriage 11. Thus the end faces 61 of these horizontal extensions constitute guides for the slide 17, and it will be appreciated that inasmuch as these end faces and also the external faces of the slide 17 are readily accessible during manufacture, a high finish can easily be imparted to them so that the slide works smoothly and maintains a close fit during prolonged use. The slide 17 is held in place by a plate 19 which overlies it and is secured to the carriage by the same screws 14 as those which fix the horizontal extensions 13 of the lugs 12. The plate 19 is pressed upwardly at 20 in the centre, as best shown in Figure 2, to accommodate a spring 21, and the spring 21 presses on the end of a plate 22 which lies in a rectangular opening 23 punched in the slide 17 (see Figure 3). The plate 22 is bent downwardly at 24 and doubled over itself to form a lug, and the lug 24 receives a screw-thread to engage an adjacent screw 25. That part of the plate 22 which engages the spring 21 is bent downwardly at 26 not only better to engage the spring 21, but also to form a stop which abuts against the end of the domed casing 20 for the spring. Thus as the stop 26 is normally held by the spring 21 pressed against the end of the dome 20, rotation of the screw 25 will serve to move the slide 17 in and out and allow it to be adjusted relatively to the edge of the razor blade 27. It will be understood that the screw 25 has a groove under its head which permits it to enter a slot in a down-turned lug 28 on the slide 17, and thus the screw 25 is held from endwise movement relatively to the slide 17 and this ensures the above described adjustment of the slide and with it the guard 15.

The plate 22, which carries the lugs 24 and 26, as can be seen from the underside plan view in Figure 3, fills the whole of the rectangular opening 23 in the frame 17, and extends forwardly to the front of the underside of the carriage 12. To permit this it has a central rectangular opening punched out which permits it to avoid fouling of the spring 21. On the front side of the carriage 12, the plate 22 is bent upwardly at 31 and it extends laterally forming a yoke 29, the ends of which embrace the outside of the frame 18 which carries the guard 15. The ends of the yoke 29 are upturned to form catches 30 (see Figure 1) which engage the edge corners of the blade 27. Thus the blade 27 is gripped under the pressure of the spring 21, which forces the plate 22 and the guard 15 rearwardly. The catches 30 are released by pressure upon the

head of the screw 25 which moves the yoke 29 bodily away from the razor blade.

The stropping mechanism of the razor comprises a pinion 37 on the pivotal spindle 33 which carries the razor blade holder 32. This pinion lies outside one of the lugs 12, as seen in Figure 1, and it engages an internal rack 38 on an actuating-lever 39 which is pivoted to the lug 12 by a screw 40. As best seen in Figure 3, the lever 39 below the pivot 40 is bent to pass under the base plate 11 of the carriage and extends across the razor below the carriage from side to side in one integral piece. On the other side of the razor it is bent up to engage a second pivot screw 41 which is axially in line with the screw 40. In the centre of the portion of the actuating-lever which extends between the screws 40 and 41, it is bent downwardly to form a U-shaped portion 42 which embraces a lug 43 formed on the upper end of a handle 44. The U-shaped central portion of the actuating-lever is pivotally secured to the lug 43 by means of two screws, one of which is shown at 45 in Figure 1. The handle 44 of the razor is hollow as shown in Figure 2 and internally screw-threaded. Within it works a bolt 46 carrying a screw-threaded head 47 to fit the screw-threads in the handle. The bolt below the screw-threads has an extension 48 which is transversely slotted at 49. Also within the handle there is a key 50 having a flat ward 51 which enters the slot 49 and is thus capable of rotating the bolt 46 while permitting longitudinal movement thereof. The key 50 has a shank 52 which extends through the lower end of the razor handle and is there secured to a knurled head 53 by which the key may be turned. This rotation of the knurled head 53 serves to advance or retract the bolt 46. The bolt 46 projects from the upper end of the handle as shown in Figure 2, and can be engaged with the underside of the plate 19 behind the domed recess 20 which contains the spring 21. When the bolt is screwed firmly against this plate, the base plate 11 together with the razor blade and all the other parts of the head of the razor are locked relatively to the handle.

It will be observed that when the razor blade 27 is held beneath the catches 30, the mechanism is locked insofar as preventing the lever 39 from actuating the pinion 37 is concerned, but this would not prevent swinging movement of the razor handle about the pivot screws 45 relatively to the lever 39. Thus the bolt 46 constitutes locking means independent of the catches 30 for locking the handle relatively to the lever and carriage when the blade is in operative shaving relation to the guard 15.

Referring to Figures 4 and 5, it will be seen that the blade-holder 32 has two leaves 62, 63 between which the blade is held. The lever leaf 62 underlies the blade 27 in the shaving position of the parts, and this leaf is provided with two spaced hinge knuckles 62^a fast upon the spindle 33. It carries upturned nibs 54 at each end between which the ends of the blade 27 are located endwise. Room is provided for the nib 54 even at the end nearest the gears 37, 38 during stropping movements of the blade 27, by reason of the fact that these gears lie outside the adjacent lug 12, and therefore, although, in the design of the razor, in order to make it compact it is necessary that the blade should occupy the full width of the razor within the lugs 12, yet there is sufficient room, as viewed in plan, for the nib 54, as

it can overlie the thickness of the adjacent lug 12 without fouling the gearing aforesaid.

The upper leaf 63 of the blade holder is provided with a single hinge knuckle 63^a between the knuckles 62^a free to turn about the spindle 33 so that it can be opened into the position shown in Figure 5, for insertion of the blade. After the blade is in place the leaf 63 is folded down on to the blade, so that it occupies the position shown in Figure 4. A split spring-collar 65 is slidably mounted on the outside of the knuckles of the leaves 62, 63 which embrace the knuckles on the spindle 33 and when the leaf 63 is folded down the spring-collar is slid over it into the position shown in Figure 4 and locks the holder closed. To open, the collar 65 is slid to one side, over part of leaf 62, thus freeing the upper leaf 63. The collar 65 is knurled on the outside to afford a better surface to engage the finger of the user.

In the use of this razor for stropping purposes the blade 27 is released from the catches 30 by pressure on the screw 25, and the bolt 46 is withdrawn by rotating the knob 53. The strop is then threaded over the rib 35 under the cross-bar 34 and over the rib 36 beneath the blade-holder. On pulling the end of the strop with one hand so as to hold it taut, grasping the handle 44 with the other hand, and moving the razor to and fro along the strop, the blade is automatically turned over by the action of the internally toothed rack 38 operating upon the actuating pinion 37, the rack being moved to and fro by the lever 42 attached to the handle. This stropping action imparts an effective stropping pressure to the blade which is not dependent upon the friction of a roller bearing upon the strop as in some existing types of safety razor. In fact it will be seen that the whole of the grip of the carriage 11 upon the strop, both that due to the ribs 35, 36 and that due to the cross-bar 34, is utilized to form a reaction pressure for the pivot of the lever 42. Thus, stropping with this device is remarkably effective.

I claim:—

1. A safety razor having a strop engaging carriage, said carriage comprising a base plate, upwardly extending lugs at each side of the base plate having horizontal extensions underlying the base, the edges of the extensions being parallel to each other, a bottom plate underlying the horizontal extensions, means for securing the horizontal extensions and the bottom plate to the base, there being a guide formed between the edges of the extensions, the base plate and the bottom plate, a sliding frame in the guide, a blade holder having a shaft pivotally mounted in said lugs, means on the sliding frame for holding the blade in a fixed cutting position, a yoke pivoted to and straddling the carriage, a pinion on the blade shaft, and a toothed sector on the yoke for oscillating the pinion during the stropping of the razor.

2. A safety razor having a strop engaging carriage, bearings in lugs on said carriage, a shaft mounted in said bearings, means for oscillating said shaft, a blade holder having a pair of leaves, each provided with a hinge knuckle, the knuckle of the one leaf being secured to the shaft while the other is free thereon, and a split ring slidably mounted on said knuckles, arranged to be shifted along the knuckles to free one of the leaves or to secure both leaves to the shaft with a blade between said leaves.
